CLAIM

The ornamental design for a projector lamp, as shown and described.

DESCRIPTION

FIG. 1 is a perspective view of a projector lamp design showing my new design.

FIG. 2 is a front view of a projector lamp.

FIG. 3 is a rear view of a projector lamp.

FIG. 4 is a left side view of a projector lamp.

FIG. 5 is a right side view of a projector lamp.

FIG. 6 is a top view of a projector lamp.

FIG. 7 is a bottom view of a projector lamp; and,

FIG. 8 is a bottom side perspective of a projector lamp.

The part of the photograph shown in a coarser dot pattern within the broken line perimeter, as well as the broken line perimeter itself, illustrates a portion of the projector lamp that forms no part of the claimed design.
